Des. 204,976
Patented June 7, 1966

204,976

VACUUM CLEANER SUCTION NOZZLE AND BRUSH COMBINATION OR SIMILAR ARTICLE

John H. Bowers, Jr., Armonk, and Ralph A. Johanson,
White Plains, N.Y., and William P. Ritzau, Stamford,
Conn., assignors to Electrolux Corporation, Old Green-
wich, Conn., a corporation of Delaware

Filed June 10, 1965, Ser. No. 85,657

Term of patent 14 years

(Cl. D9—2)

Fig. 1

Fig. 2

Fig. 3

Fig. 4

FIG. 1 is a top plan view of a vacuum cleaner suction nozzle and brush combination, showing our new design;

FIG. 2 is a front elevational view thereof;

FIG. 3 is a rear elevational view thereof; and

FIG. 4 is a side elevational view thereof.

The dominant features of our design reside in the portions shown in full lines, the fragmentary showing of the elbow being for illustrative purposes only.

We claim:

The ornamental design for a vacuum cleaner suction nozzle and brush combination or similar article, as shown and described.
